Primary Examiner — Bridget L Eland(74) *Attorney, Agent, or Firm* — Christie, Parker & Hale, LLP(57) **CLAIM**

The ornamental design for a mobile phone, as shown and described.

DESCRIPTION

FIG. 1 is a front perspective view of the mobile phone;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, shown in an in-use state; and,

FIG. 9 is a rear perspective view thereof, shown in an in-use state.

The broken lines shown in the views are included for the purpose of illustrating portions of the mobile phone that form no part of the claimed design.

1 Claim, 7 Drawing Sheets(56)
